(57) **CLAIM**

The ornamental design for a light source control unit, as shown.

DESCRIPTION

FIG. 1 is a perspective view of the light source control unit as seen from the top, rear and left side wherein the broken line disclosure is for environmental purposes only and does not form a part of the claimed design;

FIG. 2 is a right side view thereof;

FIG. 3 is a top plan view thereof;

FIG. 4 is a bottom plan view thereof;

FIG. 5 is a rear view thereof; and,

FIG. 6 is a front view thereof.
